UNITED STATES PATENT OFFICE.

HERBERT GREEN, OF CHICAGO, ILLINOIS.

AUTOMATIC ADVERTISING-CARD.

1,198,022.

Specification of Letters Patent. Patented Sept. 12, 1916.

Application filed February 15, 1915. Serial No. 8,340.

To all whom it may concern:

Be it known that I, HERBERT GREEN, a citizen of the United States, residing at Chicago, in the county of Cook and State 5 of Illinois, have invented certain new and useful Improvements in Automatic Advertising-Cards; and I do hereby declare the following to be a full, clear, and exact description of the invention, such as will enable others skilled in the art to which it 10 pertains to make and use the same.

This invention relates to advertising cards and the primary object of the invention is the provision of a card for use upon street 15 cars or other movable bodies for exhibitive advertising, which cards include means controlled by the stopping and starting of the movable body by which it is carried for moving parts of the card for increasing the 20 attractiveness of the same.

Another object of this invention is the provision of an advertising card as specified which has associated therewith a ball which is mounted in a tube for rolling from one 25 end of the tube to the other upon the stopping or starting of the car, for actuating pistons and wires for moving various parts of the advertisements.

With the foregoing and other objects in 30 view this invention consists in such novel features of construction, combination and arrangement of parts as will be hereinafter more fully described, illustrated in the accompanying drawings, and claimed.

35 In describing the invention in detail reference will be had to the accompanying drawings wherein like characters designate like or corresponding parts throughout the several views, and in which:—

40 Figure 1 is a view showing the application of the improved advertising card. Fig. 2 is a front view of the card. Fig. 3 is a rear view of the card. Fig. 4 is an enlarged sectional view of the means for operating 45 the movable section of the illustration of the card. Fig. 5 is a modified form of the mechanism illustrated in Fig. 4. Fig. 6 is a cross sectional view on the line 6—6 of Fig. 3. Fig. 7 is a cross sectional view on the line 7—7 of Fig. 5, and Fig. 8 is a cross 50 sectional view of a modified form of the advertising card. Fig. 9 is a fragmentary sectional view on the line 9—9 of Fig. 8.

Referring more particularly to the drawings, 1 designates an advertising card, such as is mounted in street cars or other movable

bodies for advertising various products of manufacture, which card has formed thereon the head and shoulders of a man as is indicated at 2 in Fig. 2 of the drawings. The 60 arm 3 of the man is pivoted upon the board 2, as is shown at 4 in Fig. 3 of the drawings, and the hand 5 has a hat 6 carried thereby. The hand 5 has a pin 7 secured thereto which pin extends through an arcuate slot 65 8 formed in the card 1. The pin 7 has wires 9 and 10 secured to the portion thereof which projects upon the rear side of the card 1.

The wires 9 and 10 are slidably mounted 70 in guiding tubes 11 and 12, which are secured to the rear sides of the card 1 by straps 13, and have communication with the opposite ends of a tube 14. The tube 14 is secured to the rear side of the card 1 by 75 straps 15, and it has detachable closing plugs 16 and 17 mounted in the ends thereof. The wires 9 and 10 extend into the tubes 14 and have pistons 18 and 19 secured thereto respectively. The pistons 18 and 19 are 80 slidably mounted within the tube, and they are forced toward the closing plugs in the ends adjacently to which they are disposed by contacts of a metallic ball 20 which is mounted within the tube 14.

85 In the operation of the improved advertising card heretofore described: when the car or movable body which carries the card 1 stops, the ball 20 will be forced forwardly within the tube 14 and engage the piston 19, forcing it toward the plug 17 and consequently operating the wire 10 longitudinally within the tube 12 and forcing the hand 5 and the pin 7 upwardly causing the hat 6 to be placed upon the head of the man. 90 When the car or vehicle starts, the ball 20 will roll rearwardly within the tube and engage the piston 18, forcing this piston toward the closing plug 16 and operating the pin 7 and the hand 5 for removing the hat 6 from the man's head. The forcing of the piston 18 toward the plug 16 will push the piston 19 forwardly within the tube positioning it away from the plug 17 and in a 95 position for actuation by the ball 20 upon the rearward rolling movement of the same.

100 Any suitable illustrative character may be used upon the card without departing from the spirit of this invention, and it may have any part thereof movable, this feature being 110 left to the discretion of the person manufacturing the device.

In Figs. 5 and 7 is shown a modified form, wherein the tubes 30 and 31 through which the wires 9' and 10' travel are formed integrally with caps 32 and 33. The caps 32 and 33 are mounted upon the exterior of the ends of the tube 14'. The tube 14' is provided with a slot 34 formed therein, through which slot projects the pointer or indicating hand 35. The pointer or indicating hand 35 has its indicating end 36 thereof inserted through the card 11 and bent for lying in abutment with the face of the card 11. The end of the indicating hand 35 which is mounted within the tube 14' has two enlarged members 37 and 38 formed thereon, between which is positioned the ball 20'. The indicator 35 is moved longitudinally along the card 11 by the rolling of the ball 20' within the tube for movement to various characters inscribed upon the face of the card 11.

In Fig. 8 of the drawings another modified form of the invention is shown, which embodies an advertising card 40 which has its lower end rolled upon itself as is shown at 41, for providing a tube in which the ball is mounted. This view also shows an embossed gutter 42 formed in the card 40 for receiving the wires which control the movable parts of the advertising card.

From the foregoing description taken in connection with the accompanying drawings the advantages of the construction and of the method of operation of the improved automatic advertising card will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:—

1. The combination with a movable body, of an advertising card structure embodying an advertising card, a character imprinted

on said card, a member movably connected to said card, said member forming a section of said character, a tube connected to the rear side of said card, pistons mounted within said tube, wires leading from said pistons operatively connected to said movable part of said character, and means for moving said piston within said tube for actuating said movable part of said character upon the starting or stopping of said movable body. 60

2. The combination with a movable body, of an advertising card structure embodying an advertising card, a character imprinted on said card, a member movably connected to the card, said member forming a section of said character, a tube connected to the rear side of said card, pistons mounted within said tube, wires leading from said piston and operatively connected to the movable part of said character, a ball mounted within said tube and adapted to alternately engage said pistons for moving said wires in different directions for operating said movable parts. 65

3. The combination with a movable body, of an advertising card structure embodying an advertising card, a character imprinted on said card, a member movably connected to the card, said member forming a part of said character, a tube connected to the rear side of the card, pistons mounted within said tube, wires leading from said pistons and operatively connected to the movable part of said character, a ball mounted within said tube and adapted for alternately engaging said pistons for moving said wires in different directions for operating said movable part, an indicating hand, a portion of said hand projecting into said tube, an enlargement formed upon a portion of said hand which is positioned in said tube, said enlargement positioned in the path of said ball for moving the hand upon movement of the ball. 85

In testimony whereof I affix my signature 90 in presence of two witnesses.

BERT GREEN.
